United States Patent

Des. 240,482
Patented July 13, 1976

240,482

ARMCHAIR

Robert Francis Voorhees, Jr., 375 Church Lane,
North Brunswick, N.J. 08902

Filed Jan. 31, 1975, Ser. No. 545,766

Term of patent 14 years

Int. Cl. D6—01

U.S. Cl. D6—69

FIG. 1

FIG. 2

FIG. 3

FIG. 4

FIG. 5

FIG. 6

FIG. 1 is a perspective view of an armchair showing my new design;

FIG. 2 is a front view of the chair shown in FIG. 1;

FIG. 3 is a side view of the chair shown in FIG. 1;

FIG. 4 is a top view of the chair shown in FIG. 1;

FIG. 5 is a back view of the chair shown in FIG. 1;

FIG. 6 is a bottom view of the chair shown in FIG. 1.

I claim:

The ornamental design for an armchair, substantially as shown.
